(57) **CLAIM**

The ornamental design for a skateboard furniture, as shown and described.

DESCRIPTION

FIG. 1 is a front elevation view of a first embodiment of the skateboard furniture;

FIG. 2 is a side elevation view thereof;

FIG. 3 is a rear elevation view thereof;

FIG. 4 is a top plan view thereof;

FIG. 5 is a bottom plan view thereof;

FIG. 6 is a front elevation view of a second embodiment of the skateboard furniture;

FIG. 7 is a side elevation view thereof;

FIG. 8 is a rear elevation view thereof;

FIG. 9 is a top plan view thereof;

FIG. 10 is a bottom plan view thereof;

FIG. 11 is a front elevation view of a third embodiment of the skateboard furniture;

FIG. 12 is a side elevation view thereof;

FIG. 13 is a rear elevation view thereof;

FIG. 14 is a top plan view thereof;

FIG. 15 is a bottom plan view thereof;

FIG. 16 is a front elevation view of a fourth embodiment of the skateboard furniture;

FIG. 17 is a side elevation view thereof;

FIG. 18 is a rear elevation view thereof;

FIG. 19 is a top plan view thereof;

FIG. 20 is a bottom plan view thereof;

FIG. 21 is a front elevation view of a fifth embodiment of the skateboard furniture;

FIG. 22 is a side elevation view thereof;

FIG. 23 is a rear elevation view thereof;

FIG. 24 is a top plan view thereof; and,

FIG. 25 is a bottom plan view thereof.

The broken lines shown in the drawings are for illustrative purposes only and form no part of the claimed design.

My skateboard furniture is characterized by having two legs pierced by an object resembling a component commonly known as a skateboard truck. The legs may be flat or contoured to resemble the typical forms of a commercial skateboard.
